ELBRIDGE R. HOLMES, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

WEFT DETECTOR FOR LOOMS.

Application filed September 24, 1924. Serial No. 739,697.

This invention relates to improvements in weft detectors for looms and more particularly to detectors for use with fine yarns. It has been found that the usual forms of detectors are likely to chafe fine yarns because of the fact that bobbins wound with yarn of the finer counts are presented to the detector mechanism a great many times before a transfer takes place.

It is the general object of my present invention to provide a shield which will permit the detecting surface to contact with the yarn on the bobbin at a slower rate of speed than that at which the bobbin is advancing to lessen the impact of the yarn against the detecting surface.

It is a more particular object of my invention to provide a detector with a shield which will normally extend beyond the detecting surface to prevent engagement of the same with the yarn but which through the intermediary of differential gearing will permit engagement with the yarn by the detecting surface and then move forwardly therefrom to permit the said detecting surface to act.

A still further object of my invention is to provide a detector shield having an initial forward rate of movement equal to that of the bobbin and thereafter having a relatively faster movement.

With these and other objects in view which will appear as the description proceeds, my invention resides in the combination and arrangement of parts hereinafter described and set forth in the claims.

In the accompanying drawings,

Fig. 1 is a side elevation of a weft detecting mechanism having my invention applied thereto,

Fig. 2 is a top plan view of the mechanism shown in Fig. 1, partly in section, showing the detector parts in normal position,

Fig. 3 is a diagrammatic view of certain parts shown in Fig. 2 with the detector parts in the position they assume when the shield is moved out of shielding position and the direct thrust of the bobbin is against the detecting surface on a non-indicating pick,

Fig. 4 is a view similar to Fig. 3 showing the detector in extreme forward position with the parts in indicating position, and

Fig. 5 is a vertical section on line 5—5 of Fig. 2.

Referring to the drawings it will be seen

that I have provided a frame 10 in which is mounted a bolt 11 which supports the feeler bed 12 adjusted as to vertical position by screw 13 in stand 10. A shaft 14 is journaled in the frame 10 and has upstanding therefrom an arm 15 fixed thereto and tending normally to move to the right as shown in Fig. 1 by a spring 16 having the ends thereof located in the hub of lever 15 and a fixed part of the stand 10, respectively. Lever 17 is also secured to shaft 14 and has pivotal connection with a controller pin 18 passing through slot 19 in a portion of the stand 10 and normally lying under and in the path of an actuator 20. When the controller 18 fails to move from under the actuator 20, the latter operates through mechanism not shown to effect a change in the running weft.

The bed 12 is provided with a slot 21 to receive a detector carrier 22 which is of tubular construction and from the rear end of which extends a detector 23 fixed thereto. A second detector 24 is pivoted as at 25 to the carrier 22 and has a roughened detecting surface thereon defined by teeth 26 proportioned to be embedded in the yarn of the bobbin to be detected. The forward end of the detector 24 is provided with an offset arm 27 the forward side of which is engaged by a rod 28 and the rear end of which is in contact with the hooked end 29 of a second rod 30. Guide bearings 31 on the rods 30 and 32 on the carrier 22 are provided for the rod 28. Said rod is acted upon by lever 15 and the rear motion of the rod 30 is limited by set screw 33 normally in contact with the adjacent portion of the bed 12. The matter thus far described is of the usual construction and may be made as set forth in Patent No. 1,500,205.

My invention relates more particularly to the shield or pad which takes the blow of the bobbin B and acts through intermediate mechanism to permit the teeth 26 to sink into the yarn at a relatively low rate of speed. Accordingly, I provide a slide 40 which fits over carrier 22 and has a bobbin engaging shield 41. Rack teeth 42 are carried by the slide 40 and rack teeth 43 are mounted on the carrier 22. The said racks are of different heights to engage pinions of different diameters, rack 42 being in mesh with pinion 44 and rack 43 meshing with pinion 45. Said pinions are secured together and are jour-

naled for free rotation in an arm 46 extending rearwardly from the cap 46' secured to the bed. Because of the different diameters of the pinions 44 and 45 the slide 40 5 will move faster than the carrier 22.

In order to prevent side motion of the detector 24 before the same has moved into complete contact with the yarn in the bobbin I provide a dog 47 pivoted as at 48 to the 10 slide 40 and having an arm 49 extending beyond the slide and engaging the outer portion thereof as indicated in Fig. 2. In order to hold the dog in normal position I provide a spring plunger 50 having a head 15 51 received by a depression in the dog and serving normally to hold the dog opposite a lug 52 formed on the detector 24. A spring 53 surrounds plunger 50 and lies between the head 51 and a guide 54 carried by 20 the slide 40.

Under normal conditions the parts will be in the position shown in Fig. 2 with the shield 41 lying rearwardly of the detectors 23 and 24 and the controller pin 18 lying 25 under actuator 20. As the bobbin engages the shield 41 the slide 40 and rack 42 will be moved forwardly to turn the pinions 44 and 45. The detector slide 22 will therefore move forwardly at a slower rate of speed 30 than the bobbin and as the latter approaches the detectors they will be embedded in the yarn. This action will continue until the thrust of the bobbin is transferred from the shield 41 to the detector 24 at which time the 35 detectors and their carrier will begin to move forwardly at the same rate of speed as that at which the bobbin is advancing. Thereafter the slide 40 will move away from the bobbin and forwardly at a relatively 40 faster rate of speed than the carrier is moving thereby moving dog 47 away from lug 52 and permitting the detectors to receive the same operative movement from the bobbin as is had by the detector set forth in 45 the aforesaid patent.

Should sufficient yarn be present the detector 24 will be held against rotation in a left hand direction about pivot 25 as shown in Fig. 3, and as the bobbin advances controller 18 will move from under actuator 20. Should insufficient yarn be present for continued weaving the pressure of rod 28 against arm 27 will be unresisted by the yarn and the detector 24 will try to move to the 50 left but will be prevented from doing so until the dog 47 has moved away from lug 52, at which time the detector will be free to move and rod 18 will remain under the actuator 20. As the latter descends it will engage the controller and move about the 55 same as a pivot to give an indication for change of operation in the loom.

From the foregoing it will be seen that I have provided a detector for use with fine 60 yarn wherein the detecting surface is pre-

sented to the yarn at a slower rate of speed than that at which the yarn or surface to be detected is moved. Thus the roughened surface of the detector is embedded between the turns of filling without subjecting the 70 latter to a sudden blow. It will also be seen that at the time the detector is called upon to give an indicating movement the shield has been moved forwardly so as not to interfere in any way with the operation 75 of the detector and that the releasing of the detector 24 by the moving of the dog 47 out of alignment with lug 52 gives the detector a sudden release so that although the teeth 26 have entered the yarn at a comparatively 80 low rate of speed yet the detector is released at the proper time to have the same motion that is characteristic of the detectors of this general type now in use.

Having thus described my invention it 85 will be apparent that changes and modifications may be made therein by those skilled in the art without departing from the spirit and scope of the invention and I do not wish to be limited to the details herein disclosed, 90 but what I claim is:

1. In a weft detector for looms, a detecting surface, a shield positioned to engage the yarn in advance of the detector, and connections between the detector and the 95 shield to move the latter forwardly at a faster rate of speed than that at which the detector moves.

2. In a weft detector for looms, a detector having a detecting surface, a shield positioned to engage the yarn in advance of the detecting surface, and geared connections 100 between the detector and the shield to move the detector forward at a slower rate of speed than that at which the shield moves 105 forwardly.

3. In a weft detector for looms, a detector having a detecting surface portions of which are formed to enter the yarn on the bobbin, and means connected to the detector 110 and deriving motion from the bobbin to move the detecting surface forward at a different rate of speed from that at which the bobbin moves.

4. In a weft detector for looms, a detector having a detecting surface portions of which are formed to enter the yarn on the bobbin, and means connected to the detector and deriving motion from the bobbin to move the detecting surface forward at a 115 slower rate of speed from that at which the bobbin moves.

5. In a weft detector for looms, a detector having a detecting surface, a non-detecting surface positioned to engage the bobbin before the latter engages the detecting surface, and means to move the non-detecting surface in the same direction in which the 125 bobbin is traveling at a slow rate of speed until said detector is in full engagement 130

with the bobbin and to thereafter move the non-detecting surface in the same direction in which the bobbin is moving but at a faster rate than that at which the bobbin is moving.

6. In a weft detector for looms, a detecting surface, a non-detecting surface positioned for engagement with the bobbin before the latter engages the detecting surface, and differential gearing to move said surfaces at different rates of speed, to cause the bobbin first to engage the non-detecting surface without engaging the detecting surface and to thereafter engage the detecting surface without engaging the non-detecting surface as the bobbin continues to move.

7. In a weft detector for looms, a detecting surface, a non-detecting surface positioned for engagement with the bobbin before the latter engages the detecting surface, and differential gearing to move said surfaces at different rates of speed.

8. In a weft detector for looms, a detector having a movement in the direction of the length of the bobbin at the time of indication of weft exhaustion, means acting to give said detector an angular movement as soon as the said detector moves forwardly, a shield to engage the bobbin before the detector engages the bobbin, means to move the detector forwardly with the bobbin at a slower rate of speed than that at which the

bobbin is advancing, and means to prevent the detector from having an angular movement until after the shield has passed in front of the detecting surface of the angularly movable detector.

9. In a detector for looms, a detector movable forwardly with the bobbin, means to engage the bobbin before the detector is engaged thereby, and means to move the detecting surface forwardly at a slower rate of speed than that at which the bobbin is moving for the first part of the detecting stroke and to thereafter permit the detecting surface to move forwardly with the bobbin in contact therewith at the same rate of speed at which the bobbin is moving.

10. In a weft detector for looms, a pair of detectors, a carrier for said detectors, one of said detectors being angularly movable with respect to the other and movable on the carrier, a shield to engage the bobbin before either of those detectors is engaged by the same, and geared connections between the shield and the carrier to move said carrier forwardly first at a slower rate of speed than that at which the bobbin is moving and then at the same rate of speed as that at which the bobbin is moving.

In testimony whereof I have hereunto affixed my signature.

ELBRIDGE R. HOLMES.
